3 Sheets-Sheet 3

UNITED STATES PATENT OFFICE.

CLIFTON D. PETTIS, OF NEW YORK, N. Y.

CASTING MOLD.

Application filed April 11, 1924. Serial No. 705,775.

To all whom it may concern:

Be it known that I, CLIFTON D. PETTIS, a citizen of the United States, and a resident of New York city, in the county and State of New York, have invented certain new and useful Improvements in Casting Molds, of which the following is a specification.

This invention relates to molds for casting metal but more particularly to that class 10 of casting molds designed to be repeatedly used in the casting operation and commonly designated "permanent molds."

The primary object of the invention is to produce a mold of this type which is simple 15 and durable in construction and which may be quickly and easily operated to provide a large output.

Further important objects are to provide a simple and efficient means for supporting 20 an insert within the mold cavity during the casting operation, to provide in the mold improved means for holding the mold sections in closed position during the casting operation, to provide an improved construction 25 to close the mold, to facilitate the placing of this closure upon the drag prior to the casting operation and its removal therefrom upon the completion of such operation, to provide effective venting of the 30 gases from the mold, to prevent injury to the refractories, and in general to provide an improved casting mold.

The many other objects and advantages 35 of my invention will be better understood by reference to the following specification when considered in connection with the accompanying drawings illustrating certain selected embodiments thereof, in which:

The general construction of my improved 40 casting mold is similar in character to that forming the subject matter of my pending applications, Serial No. 633,131, filed April 19, 1923; Serial No. 633,822, filed April 23, 1923, and Serial No. 637,165, filed May 7, 45 1923, and reference may be had thereto for a more full description.

While I have chosen to illustrate the principles of my invention in a mold designed 50 particularly for the casting of railway brake shoes, it will be readily appreciated that the same are equally applicable to molds for casting any other articles.

Referring to the drawing, Figure 1 is a side elevation of a mold for casting brake shoes, the parts being in closed position. 55

Fig. 2 is a plan view of the mold shown in Fig. 1.

Fig. 3 is the same as Fig. 1, end elevation.

Fig. 4 is a transverse vertical section on the line 4—4 of Fig. 2.

Fig. 5 is a longitudinal vertical section on the line 5—5 of Fig. 2.

Fig. 6 is a detail plan view of the drag.

Fig. 7 is an inverted plan view of the mold closure with back unit in position and ready to be placed in the mold. 65

Fig. 8 is a longitudinal vertical section on the line 8—8 of Fig. 7.

Fig. 9 is a transverse section on line 9—9 of Fig. 7, and 70

Fig. 10 is a detail perspective view.

The casting mold in the present embodiment is mounted on a base A and comprises a plurality of separable members forming a flask or holder, each member carrying a portion of the molding receptacle. The base A is provided with oppositely disposed lugs 15 and 16, which support a rod 17 on which are pivotally mounted the two side members B, B of the mold. Similar rods 18 and 19 are supported by lugs 20 and 21 respectively and the end members C, C of the mold are pivotally mounted on these rods. The members B, B are operated by cams 22, 22 co-acting with lugs 23 on these members. The cams 22, 22 are each secured upon a sleeve 30 revolvable upon oppositely disposed stud shafts 24 supported by upstanding lugs 25 on the base A and these sleeves are adapted to be manually 85 rotated by means of operating levers 26.

The members B, B are alike in form except that their arrangement is reversed. Each of these members includes a metal holder or flask section in which are mounted a plurality of blocks 28 forming a portion of the molding receptacle. In the present embodiment these blocks are of highly refractory material, though metal blocks may be substituted for any of these where chilling action is desired. The outer wall of the member P is formed by a separable plate 32 secured to the member by screws 33 or other suitable means. This 95 100

plate is removed to permit the insertion or removal of the blocks 28. The plate 32 is preferably provided upon its inner face with inwardly projecting ribs as 34 which press 6 against the rear wall of the blocks or refractories 28 and hold these firmly against the opposing wall formed by the upstanding face plate 35. The plate 35 forms the wearing or contacting surface when the 10 mold is in closed position. The walls of the member B are preferably provided with openings as at 36 to permit the venting of the gases and the rapid cooling refractories. Integral Jugs 37 are provided on the top 15 walls of these members for the purpose which will be presently described. The refractories 28 in the present embodiment, form the bottom and side walls of the molding receptacle within which is the mold cavity 38. The portion 40 of the inner wall 39 of each of the members B forms a contact surface for the top section of the mold, to be presently described. Plates as 40' at the ends of these members perform the same 20 function as the plates 35, and in addition serve to protect the edges of the refractories. The end members C of the mold are alike in construction except that their position is reversed. Each of these members 25 comprises a holder or flask section 41 preferably of metal and one or more refractories as 42 mounted therein and forming a portion of the molding receptacle. This member has an opening as 43 in its outer wall 44 to admit the refractories. This opening is closed by a plate 45 screwed or otherwise fastened to the member as at 46. Lugs 47, corresponding to the lugs 23 on the side members, are provided on this plate to enable the end 30 members to be moved by the operating cams 48 to open and closed positions. These cams are mounted and operated in substantially the same manner as the cams 22. Ribs 49 on the plate 45 press the refractories firmly 35 against the inner wall of the member. The refractories project through an opening 50 in such inner wall and have their exposed inner faces 51 preferably flush with the corresponding face of the wall, the metal wall 40 protecting the refractories against injury. A portion of these refractories forms the end wall of the molding receptacle. The outer end portions of these end members are 45 preferably wider to form shoulders as 52 which abut in closed position against corresponding shoulders 53 on the side members to lock these side members in such position. The top or closure member D of the mold in the present embodiment is composed of 50 a plurality of metal sections. This mold is designed to cast a railway brake shoe in which is incorporated a ductile metal reinforcing plate or back as 60. The central section of the member comprises two blocks 61 and a like number of blocks 62, these blocks being held together by rods 63 which are enlarged at their ends. The back 60 together with the center lug 64 and usual core 65 are secured as a unit to the central section by clips 66. These clips in the present embodiment are formed from a flat strip of metal. One end 67 of the strip is initially bent as indicated in Fig. 10. The clips thus formed are inserted between the blocks 61 and 62 from the face-side until the bent 70 ends come in contact with the back 60 resting on the inverted section. The ends 68, then projecting beyond the top surface of the blocks, are bent downwardly as shown in Fig. 8. The center blocks 62 project above 75 the blocks 61 and are provided with registering orifices as 69 to enable the closure member to be lifted by suitable hoisting means. The clips pass through opening 70 between the blocks and these openings are preferably 80 slightly wider than the clips as at 71 so that some additional venting may occur. Grooves as 72 may be formed in the blocks 62 both where these blocks contact with the blocks 61 and where the blocks come together in 85 the center. These grooves are deep enough to permit the passage of the gases but not to permit the melted metal to flow therein. At opposite ends of the center section are 90 sections 73 and 74, the section 73 forming the pouring gate and being provided with a pouring passage 75 therethrough for this purpose. Recesses 76 and 77 for the brake shoe end lugs are respectively provided in the sections. The sections of the closure 95 member are provided with a shoulder as 78 which rests on top of the flask to cause the member to be supported thereby. The upper face 79 on the projection forming this shoulder is preferably beveled and this face 100 is engaged by the lugs 37 when the mold is closed, to thereby lock the closure in place. The section 73 of the closure member comprises a pair of blocks 80 having the passage 75 formed in the opposite walls of these 105 blocks. Ribs 81 on one of these blocks fit within corresponding depressions in the other, holding these blocks in alignment and preventing the passage of melted metal therebetween. A depression 82 is formed in 110 the upper face of the section 74 for the purpose of reducing the weight of that section. Stops 85 are preferably provided on the base to co-act with the lugs 23 to limit the opening movement of the side members. 115 When these side members are fully open, the closure member may be lowered into the mold, the spacing of the lugs 37 then being sufficient to permit the passage of the closure member. The shoulder 78 on the closure rests on the inside corners of the side members while these side members are in 120 open position. In assembling the closure member, the center section with back attached is placed 125 130

in the mold. The sections 73 and 74 are then placed in position on the reinforcing back, and the side members are moved to closed position, the lugs 37 holding all sections of the closure firmly in position. The end members are now moved to closed position and the mold is ready to receive the melted metal. After the casting has solidified sufficiently, the end members are moved to open position, 10 then one or both of the side members, and the casting and sections of the top or closure member are together lifted from the remaining portions of the mold, the casting being held by the clips 66. These clips are then 15 straightened at their upper ends, and the shoe casting drops away. The mold is then ready to be reassembled for a new pouring.

From the foregoing description it will be readily evident that my improved mold is 20 simple and desirable in construction and may be easily operated to provide a large output. A simple and effective means has been provided for suspending the metal insert within the mold cavity during the casting operation. 25 The sections of the mold are securely held in closed position. The construction for closing the molding receptacle is simple and advantageous. The closure member may be easily placed upon the drag or removed 30 therefrom. The entire construction provides free venting of the gases from the mold and protects the refractories from injury.

I am aware that numerous changes in the form and arrangement of parts of my mold 35 may be made by anyone skilled in the art without departing from the spirit of my invention, and I reserve the right to make all such as fairly fall within the scope of the following claims.

40 I claim as my invention:

1. A mold for making castings, comprising an openable multi-part drag having a molding cavity therein formed partially by each 45 of the parts but open at the top, a closure for said cavity forming a continuous span between the parts of the drag, and means on said drag for clamping said closure in position by the closing of the drag.

2. A mold for making castings, comprising 50 relatively movable mold members and a closure member adapted to rest thereon, said movable members being constructed to directly clamp and interlock with the body of the closure member for holding said closure member against removal while the movable members are in closed position.

3. A mold for making castings, comprising 55 relatively movable members having a mold cavity formed thereby and open at the top throughout its entire length, and a sectional closure for said cavity clamped and held against removal by said movable members when in closed position.

4. A mold for making castings, comprising 60 a multi-part drag having a mold cavity

formed thereby and open at the top throughout its entire length, and a separate sectional top closure for said cavity fitting within the upper part of said cavity and having body portions thereof between the drag 70 parts and other body portions overlying and resting on each of said drag parts.

5. A mold for making castings, comprising 75 relatively movable members having a mold cavity formed thereby and open at the top, a closure for said cavity adapted to be loosely placed upon said side members when in normal open position, and means operable to interlock the body of said closure and secure said closure in position by the bringing of said members to closed position.

6. A mold for making castings, comprising 80 relatively movable members having a mold cavity formed thereby and open at the top, a closure for said cavity adapted to be placed over said cavity when said members are in normal position to permit removal of a finished casting, and interlocking means on said members and closure body 85 operable to secure said closure on said members by the bringing of said members to closed position.

7. A permanent mold for making metal 90 castings, comprising relatively movable side members having a mold cavity formed partially in each of said members and open at the top, a closure for said cavity adapted to be placed upon said members in open position, and lugs on said members interlocking 95 with portions of said closure to secure said closure on said members when said members are brought to closed position.

8. A mold for making castings having 100 a mold cavity with one open side, and a closure for said side including a separable section, said closure and said section both cooperating with the same open side of the mold and each constituting a partial closing means therefor, said closure embodying 105 means for bodily removing it together with a finished casting.

9. A mold for making castings having a mold cavity with one open side, and a closure for said side including a plurality of 110 separable sections, said closure and said separable sections all cooperating with the same open side of the mold and each constituting a partial closing means therefor, said closure embodying means for bodily removing it together with a finished casting.

10. A permanent mold for making metal 115 castings, comprising a drag having a mold cavity therein open at the top, and a closure for said cavity adapted to rest on said drag and including a center section and separable end sections.

11. A permanent mold for making metal 120 castings, comprising a drag having a mold cavity therein open at the top, and a closure for said cavity adapted to rest on said drag 125

- and including a center section and separable end sections, one of said end sections forming the pouring gate of the mold.
12. A permanent mold for making metal castings, comprising a drag having a mold cavity formed therein and open at the top, and a closure for said cavity separate from said drag and adapted to rest thereon, said closure comprising a plurality of blocks with certain of said blocks secured together and certain other blocks unattached.
13. A permanent mold for making metal castings, comprising a drag having a mold cavity formed therein and open at the top, and a closure for said cavity separate from said drag and adapted to rest thereon, said closure comprising a plurality of separate sections certain of which include a plurality of blocks.
14. A permanent mold for making metal castings, comprising a drag having a mold cavity formed therein and open at the top, and a closure for said cavity separate from said drag and adapted to rest thereon, said closure comprising a central section and separate end sections, the central section being formed of a plurality of blocks attached together.
15. A mold for making castings, comprising a multi-member drag having the parting line extending longitudinally of the mold and substantially centrally of the mold cavity, said cavity being open at the top, and a closure for said top divided transversely of the mold into sections, at least some of said sections resting on one drag member and the opposite end resting on the other drag member.
16. A mold for making castings, comprising a drag having a mold cavity therein open at the top, and a closure for said cavity separate from said drag and comprising a plurality of separate sections having a common supporting plate adapted to become incorporated in a finished casting.
17. A mold for making castings, comprising relatively movable drag members having a mold cavity therein open at the top, a closure for said cavity formed in bodily removable sections, and means on said drag members for locking the sections of the closure thereon by the moving of said members to closed position.
18. A permanent mold for making castings, comprising a drag having a mold cavity therein open at the top only, a bodily removable closure for said cavity comprising a plurality of preformed independent sections all cooperating with said open top, and means for attaching to at least one of said sections an insert to be embedded in the casting.
19. A permanent mold for making castings, comprising a drag having a mold cavity therein open at the top, a closure for said cavity comprising a plurality of sections, one of said sections being formed of a plurality of blocks, and means extending between said blocks and engaged with a unit and the top of the section to suspend the unit in the mold cavity.
20. The combination with a permanent mold for making castings, comprising a drag having a mold cavity therein open at the top and a closure for said top, of a member for suspending a unit in the mold cavity comprising a flat strip of metal having on each end a transversely extending head.
21. A permanent mold for making castings, comprising a drag having a mold cavity therein open at the top and a closure for said top having grooves extending therethrough and communicating with the mold cavity, and flat strips of metal extending through said grooves and having angularly disposed means adapted to engage the closure and a unit to be embedded in the casting to suspend the unit in the mold cavity.
22. A permanent mold for making castings including relatively movable side and end members, at least one side member being movable in a direction substantially normal to the direction of movement of one of the end members, and a shoulder on one of said members adapted to overlie a portion of the other member when said members are in closed position to lock said other member in this position.
23. A permanent mold for making castings including relatively movable side and end members, at least one side member being movable in a direction substantially normal to the direction of movement of one of the end members, and shoulders on said end members adapted to overlie portions of said side members when said members are in closed position to retain said side members in said position, said side members being released by the opening of said end members.
24. In a casting mold, a pouring gate comprising a pair of oppositely disposed blocks having the pouring passage formed partially in each, and a rib on the face of one of said blocks lying within a corresponding groove in the opposing face of the other block.
25. A mold for making castings, comprising relatively movable members having a mold cavity formed thereby and open at the top, a bodily removable closure for said cavity adapted to be placed upon said side members when in the normal open position to which the parts are moved to permit removal of a finished casting, means acting to interlock with and secure said closure on said members as said members are brought to closed position, and means limiting the

opening movement of said side members to properly position said members to receive said closure.

26. As an article of manufacture, a mold having a mold cavity, and a separable top closure for said cavity comprising a plurality of sections abutting intermediate the ends of the mold cavity and having means adapted to become incorporated with the casting, said top closure being bodily removable with the casting.

27. As an article of manufacture, a mold having a mold cavity, and a separable top closure removable bodily as a unit with a finished casting, said top closure comprising a plurality of sections abutting intermediate the ends of the mold cavity.

28. As an article of manufacture, a mold having a mold cavity, and a separable top closure for said cavity removable bodily with a finished casting, said top closure comprising a plurality of sections abutting intermediate the ends of the mold cavity and including a metal body adapted to become incorporated in a casting and detachably anchored to the top closure.

29. As an article of manufacture, a mold having a mold cavity with a single open side, a bodily removable closure for said single open side including a separable section, and a metal plate cooperating with said closure and adapted to become incorporated in a finished casting.

30. As an article of manufacture, a mold having a mold cavity with a single open side, a bodily removable closure for said single open side including a plurality of

separable sections, and a metal plate cooperating with said closure and adapted to become incorporated in a finished casting. 40

31. As an article of manufacture, a mold having a mold cavity with one open side, and a closure for said side adapted to rest on the mold, said closure including a center section and separable end sections, one of 45 said sections forming the pouring gate for the mold.

32. A mold comprising at least one pivotally mounted side member, at least one end member movable about an axis substantially 50 normal to the pivotal mounting of the side member, and interlocking shoulders on at least one side member and one end member, locking one of the members against opening movement until the other member has 55 first been moved to open position.

33. A mold for making castings, comprising relatively movable members and a sectional closure member adapted to rest thereon, said movable members directly 60 clamping and interlocking with the sides of the body of the closure member sections for holding said sections against removal while the movable members are in closed position.

34. A mold for making castings, comprising relatively movable members, and a closure member adapted to rest thereon, said movable members directly clamping and interlocking with the sides of the body of the closure member for holding the closure member against removal while the movable members are in closed position. 70

CLIFTON D. PETTIS.
